UNITED STATES PATENT OFFICE.

HOLLIS C. TROUT, OF MINNEAPOLIS, MINNESOTA.

LETTER-BOX.

SPECIFICATION forming part of Letters Patent No. 229,209, dated June 22, 1880.

Application filed December 11, 1879.

To all whom it may concern:

Be it known that I, HOLLIS C. TROUT, of Minneapolis, in the county of Hennepin and State of Minnesota, have invented a new and Improved Letter-Box, of which the following is a specification.

The object of my invention is to provide a receptacle for mail-matter so arranged that its interior can be quickly and easily inspected without opening the cover.

In the accompanying drawings, Figure 1 is a side elevation of my improved box; and Fig. 2 is a vertical cross-section of the same, taken on line *xx* of Fig. 1.

Similar letters of reference indicate corresponding parts.

Referring to the drawings, *A A* are the ends of the mail-box. The tops of ends *A A* are projected upward into the form of an inverted *V*. To one side, *a*, of the incline formed by this construction of the ends *A A* is fixed a plate, *b*, which forms one-half of the cover.

B is the hinged cover placed on the inclined sides *a'* of ends *A*, and connected at each end by an arm, *C*, rigidly attached to the under side of cover *B*, with the ends *A*, by pivoting the end *c* of said arms to the inside of said ends, in the manner clearly shown in Fig. 2. This mode of connecting cover *B* with the box permits the said cover to be drawn down on the inclined sides *a'* to close the entrance to the box, and when thrown up to open the box the upper edge, *d*, is projected over the upper edge, *e*, of cover *b*, and any water that may have collected on cover *B* will be thrown off

on cover *b* instead of falling down within the box.

The sides *D* of the box may be formed of wire-gauze, as shown in the drawings, or they may be formed of glass, or glass protected by an exterior covering of wire-gauze, or any other material that will permit a quick inspection of the box through the sides.

The box thus constructed may have its ends *A A* attached to standards *E E* rising from a plate, *F*, when the bottom of the box and the sides are one, as in the drawings; but if it is provided with a wooden or metal bottom it may be set on a post or any other suitable support.

The box is intended principally for the use of residences and stores as a receptacle for newspapers; but it may also be used as a receptacle for other mail-matter.

Having thus described my invention, I claim as new and desire to secure by Letters Patent—

A mail-box having ends *A* projected up in the form of an inverted *V*, the plate *b* on the inclined side *a*, the hinged cover *B*, arranged on the inclined sides *a'* and connected at each end by the arm *C*, whose end is pivoted to the inside of ends *A*, and the wire-gauze *D*, the whole supported upon a frame, *E E F*, as shown and described.

HOLLIS C. TROUT.
